ATTORNEY

UNITED STATES PATENT OFFICE.

THOMAS C. DINGMAN, OF SOUTH BEND, INDIANA, ASSIGNOR TO THE WHITE MOTOR COMPANY, OF CLEVELAND, OHIO, A CORPORATION OF OHIO.

DESIGN FOR AN INSTRUMENT PANEL.

Application filed February 19, 1927. Serial No. 20,811. Term of patent 7 years.

To all whom it may concern:

Be it known that I, THOMAS C. DINGMAN, a citizen of the United States, residing at 1110 Huey Street, in the city of South Bend, county of St. Joseph, and State of Indiana, have invented a new, original, and ornamental Design for Instrument Panels, of which the following is a specification, reference being had to the accompanying drawing, forming part thereof.

In the said drawing, Figure 1 is a vertical

perspective of an instrument panel showing my new design.

Figure 2 is an elevational view of the left hand side of the instrument panel, and

Figure 3 is a front view of the instrument panel.

I claim:

The ornamental design for an instrument panel as shown.

THOMAS C. DINGMAN.
